UNITED STATES PATENT OFFICE.

ANTON REZNICEK, OF JERSEY CITY, NEW JERSEY.

SHIRT.

1,110,822.

Specification of Letters Patent. Patented Sept. 15, 1914.

Application filed November 17, 1913. Serial No. 801,440.

To all whom it may concern:

Be it known that I, ANTON REZNICEK, a citizen of the United States of America, and a resident of Jersey City, in the county of Hudson and State of New Jersey, have invented certain new and useful Improvements in Shirts, of which the following is a specification.

This invention relates to shirts having 10 trousers suspending means connected thereto and substantially concealed thereby.

In the accompanying drawing, Figure 1 is an elevation of a shirt embodying the invention, attached to a pair of trousers, Fig. 2 15 is a side-view, the shirt being shown in vertical section, and Fig. 3 is a horizontal section on line 3—3 of Fig. 1.

Similar reference numerals indicate corresponding parts in each of the figures.

20 In the form of embodiment herein shown, the body 10 of the shirt is provided with two inside front shoulder tabs 21 and 31 dependent from the shoulder seams about midway of the length thereof between the 25 neck and the arm scyes and with an inside back tab 29 dependent from the yoke. These tabs are provided respectively with fastening members 20, 30 and 28 in the form of buttons. The body of the shirt is provided 30 in its front with chest slots 11 and 12 and at its back with a slot 40 preferably on a level with the chest slots 11 and 12. These slots are here called chest slots because they come opposite the chest of the wearer when 35 the shirt is on the body and they are thus distinguished by location from slots located opposite or adjacent the waist of the wearer where they would interfere with the buttoning of the suspender straps. Front straps 13 and 14 are detachably attached at their upper 40 ends to the front inside shoulder tabs 21 and 31 at the shoulders and depend downward therefrom and a back strap 25 is detachably connected with the back tab 29 just below the neck and depends therefrom. The lower portions of these straps are folded upward forming loops 15, 16 and 26 which are adjustable higher or lower. The means 45 of adjustment shown comprise a series of buttonholes 23 disposed at different heights on the body of the strap 13, a similar series of buttonholes 33 disposed in the body of the strap 14 and a similar series of buttonholes

34 disposed in the body of the strap 25. The opposite ends of the straps 13, 14 and 25 are provided respectively with fastening members 22, 32 and 24 in the form of buttons or otherwise, these buttons being severally adapted to engage the buttonholes 23, 33 and 34 of the bodies of said straps after the lower portions thereof are folded upward to form the loops aforesaid. The looped ends 15, 16 and 26 of the straps 13, 14 and 25 depend through the chest slots 11, 12 and back slot 40 and are exposed at their lower ends outside the shirt. Suspender ends 17, 18 and 27 are passed through these outside loops 15, 16 and 26 and their opposite ends are adapted to engage the trousers buttons. In this construction the main portions of the suspender straps are concealed underneath the shirt while the suspender ends are exposed in front and are free to slide in the supporting loops of the straps without interference of the shirt body with their movements. The suspender straps are independent of each other and can be readily detached from the tabs when the shirt is to be sent to the laundry.

Suitable flaps 35, 36 and 37 are attached to the shirt-body immediately above the openings in the same, and extend downwardly over the openings, thereby closing the same to the eye, and also protecting the opening.

It is obvious that in place of buttons and buttonholes as adjustable attaching means, buckles or other devices might be employed, as is well-known in suspender construction.

The invention is not limited to the specific structure shown, but changes may be made therefrom without departing from the spirit of the invention as set forth in the claim.

I claim:

A shirt having inside front tabs dependent from the shoulders, an inside back tab dependent from the yoke, two front chest slots disposed vertically below said shoulder tabs, a back slot disposed vertically below said back tab, independent adjustable front straps detachably connected with said front tabs at the shoulders and provided with looped ends depending through said front chest slots outside the shirt, an independent adjustable back strap detachably connected with said back tab at the shoulders and having a loop depending through said back

slot outside the shirt, and suspender ends looped through the loops of said straps outside the shirt body and adapted to engage the trousers buttons, said chest slots being disposed above the connection of the suspender ends with the loops of said straps.

In testimony that I claim the foregoing

as my invention, I have signed my name in presence of two subscribing witnesses.

ANTON REZNICEK.
